UNITED STATES PATENT OFFICE.

WILHELM GRIESSE, OF JOPLIN, MISSOURI, ASSIGNOR TO WILLIAM C. GRIESSE, OF PITTSBURGH, PENNSYLVANIA.

DEEP-SEA CONSTRUCTION.

1,391,380.

Specification of Letters Patent. Patented Sept. 20, 1921.

Application filed May 15, 1920. Serial No. 381,538.

To all whom it may concern:

Be it known that I, WILHELM GRIESSE, a citizen of the United States, residing at Joplin, in the county of Jasper and State 5 of Missouri, have invented new and useful Improvements in Deep-Sea Constructions, of which the following is a specification.

This invention relates to a protective and supporting construction for use in forming 10 wharves, piers, docks, sea-walls, jetties, cofferdams and other similar constructions and adapted for installation or erection in various bodies of water as seas, lakes, rivers, etc. The improved construction may also be ad- 15 vantageously employed in building foundations and for use in the construction of bridges and also as a supporting means for superstructures adapted to be maintained above a water level or to be protected from 20 water pressure, as for instance sea waves.

The primary object of my invention however, is to provide a novel construction which may be readily built in deep water. To accomplish this object, the vertical sup- 25 porting members of the structure are gradu- ally sunk by being filled with a heavy plastic material such as concrete, until they lodge on the sea bottom.

The distinguishing feature of the im- 30 proved construction consists in the provi- sion of tubes, tanks, or hollow piles of cy- lindrical form which are disposed vertically and adapted to be attached to each other by braces or connectors of various forms which 35 are so arranged that an automatic settling or vertical movement of the tubes, tanks, or piles may ensue relatively to irregularities of contour of the bottoms of bodies of water in which the improved construction may 40 be erected, the several tubes, tanks or hollow piles being so associated as to resist acci- dental detachment by lateral strains brought to bear thereon, or by direct front impacts of bodies of water. The tubes, cylinders or 45 hollow piles may also be arranged to form a wall of any shape by properly disposing and connecting the braces or other attaching devices therefor, and in some instances a number of the tubes, cylinders or hollow 50 piles may be closely associated and strongly tied to each other to form as a unit a pillar or pedestal. The tubes, cylinders or piles after being arranged in the form desired

may be completely filled with cement or concrete to thereby strengthen and give the 55 same material weight with obvious advantages in maintaining the protective and supporting features of the improved construction, and moreover, by thus completely filling the tubes, cylinders or piles with cement 60 the said components will be more firmly embedded on the sea bottom and therefore better enabled to resist displacement.

From the foregoing it will be understood that the improved construction may be em- 65 ployed in a great variety of ways and will completely overcome many of the disadvan- tages and defects heretofore experienced in erecting absolutely water tight walls and cofferdams and other similar organizations. 70 The attached or connected tubes, tanks or piles may be made in sections of any length and diameter, and their height may be as great as desired, it being proposed to add sections on sections, as the successive sec- 75 tions sink under the weight of the concrete contained within the tubular member and as may be required to obtain a uniform top level and also to so dispose the braces or connectors in relation to various parts of 80 the tubes, cylinders, tanks, or piles as will give the best results from a strengthening and reinforcing standpoint.

The improved construction is illustrated in various forms in the accompanying 85 drawings, and therein:—

Figure 1 is a sectional elevation of a num- 90 ber of the units of the improved construc- tion shown assembled and the tubes, cylinders, tanks or piles in part fully depressed and in part in different stages of settling.

Fig. 2 is a top plan view of a number of the tubes, cylinders, tanks or piles assembled in wall and supporting form and attached by various forms of braces and connectors. 95

Fig. 3 is a side elevation illustrating two of the tubes, cylinders or piles and a double bracing means therebetween.

Fig. 4 is a top plan view of a portion of the structure shown by Fig. 3. 100

Fig. 5 is a detail elevation showing the bracing means in single form.

Fig. 6 is a horizontal section through interlocking bracing means and connectors for use with the various arrangements of 105 the tubes, cylinders or piles.

Fig. 7 is a detail horizontal section of a further modification of assembling the parts of the bracing means.

Fig. 8 is a diagrammatic plan view showing the manner of assembling a plurality of the tubes, cylinders or piles as an inclosing wall or as a support for a superstructure.

The essential units of the improved construction comprise tubes, cylinders, tanks or hollow piles 5 and braces or connectors 6 disposed between the units 5 for holding the latter in upright position and also in some instances to contribute to the formation of a water tight inclosure. In the structure as shown by Fig. 1 the tubes, cylinders, or hollow piles constituting the units 5 are composed of a plurality of sections 7 which may be of various lengths and also differ in diameter, the general dimensions of these units 5 depending upon the character of the structure of which they form a part. The units 5 and 6 as shown by Fig. 1 will have the appearance in top plan view as shown in the upper part of Fig. 2, each unit 5 being provided with a plurality of units 6 radiating from the outer sides thereof either at diametrically opposite points or at intervals between such diametric points in accordance with the attachment thereto of the connectors or bracing means between the several units 5. The units 6, as shown more clearly by Fig. 2, are in the form of I-beams which are connected to the outer sides of the units 5 in any suitable manner, and the simplified attaching means or connectors, or units 6, as shown by Fig. 1 and the upper portion of Fig. 2 consist of opposite channel irons 7 bolted together as at 8 and having the outer flanges of the I-beams projecting from adjacent units 5 held loosely within the channel irons. This same scheme is carried out in all of the bracing organizations, or the units 6 attached to the units 5 are utilized in various ways, or analogous flanged devices are associated with channel irons of various types in accordance with the angles at which the braces or connectors are disposed.

In Fig. 2 a part of the units 6 at the inner portions of the units 5 movably engage channel irons 10 having securing flanges 11 attached to elongated braces or connectors 12, the latter being disposed in various angular positions relatively to the inner supporting units 5^a which are in all respects similar to the units 5 and are equipped with units 6 of I-beam form in various positions as shown to accommodate the disposition or particular arrangement of the braces illustrated by Fig. 2. From one unit 5 a brace 13 may extend and be secured to a group of the channel irons 10 adjacent to one of the supporting units 5^a, or two of these similar braces 14 and 15 may intersect at an angle 16 and movably engage a junction coupling 16

composed of channel irons 17 and flanged heads 18 on the adjacent ends of the braces 14 and 15, the latter in this arrangement being made in sections. As a further provision the brace or connector 15 may intersect or junction with braces 19, 20 and 21 by similar channel irons and flanged heads and I-beam structures as at 22, the several braces or connectors 15, 19, 20 and 21 extending from the outer units 5 and connected to the inner units 5^a. In a similar manner the units 5^a may be attached and strengthened by a brace or connector 23 of suitable length. It will be understood that all of the connections of these braces, or the flanged heads engaging the channel iron terminals and junction organizations, will be free to move, or the flanged heads will be movable in the channel irons so as to accommodate a settling of the parts. Again, referring to Fig. 1 and particularly to the tubes, cylinders or hollow pipes constituting the units 5, it will be seen that the said units have closed conical bottoms 24, and at suitable elevations within these units are T-edges 25 to strengthen the parts of the unit 5 in which they are disposed sufficiently to resist crushing strain thereon, particularly when the said units 5 are depressed in water of considerable depth where there is a strong pressure and prior to filling the tubes, cylinders or hollow piles in a manner which will be presently explained. After the tubes, cylinders or hollow piles, or the units 5 settle, sections 27 will be secured to the upper ends thereof of different widths to accommodate the differentiation in settling movement of the said units 5 and to have the upper end of each unit terminate level with the upper ends of adjacent units and also with the upper ends of the braces or connectors 6 for these units.

As shown by Figs. 3, 4 and 5 the connecting braces between the units 5 may be of open structure and comprise a plurality of vertically disposed T-beams 28 engaging intermediate channel irons 29 bolted to each other as at 30 between these open units, the T-irons or beams 28 adjacent to the units 5 being movably embraced by channel members 31 secured to the units 5 as shown by Fig. 4. Extending horizontally across and diagonally between the T-beams or irons 28 are metal braces 32 terminally secured to the said beams or irons and also to each other. In Fig. 3 two of these open brace structures are illustrated between each pair of units 5, and in Fig. 5 a single similar open bracing unit is shown between each pair of units 5 and is of the same construction as the bracing units just described and has similar reference characters applied thereto.

In Fig. 6 a brace junction is illustrated and is particularly adapted for connection to a plurality of units 5 or other bracing de-

vices arranged therearound, this junction organization comprising I-beams 33 secured to the intermediate portion of a longer I-beam 34 arranged at right angles thereto, 5 the outer flanged heads of these I-beams 33 and 34 being movably held between the channel irons 35 which are bolted together or tied as at 36. From the outer portions of the channel irons 35 I-beams 37 of any 10 length of web extend and are adapted to engage units 5 in a manner hereinbefore explained. In Fig. 7 a further form of brace junction is illustrated and consists of an I-beam 38 having its inner flanged head held 15 between seat members 39 secured to the web of an I-beam 40, the seat members 39 being disposed in opposed pairs and also serving to receive angle members 41 secured on a brace or connector 42 which may be suitably attached to one of the units 5 or to other bracing means. The outer flanged head or end of the I-beam 38 engages channel irons 43 similar to the channel irons 35 hereinbefore explained. 20 25 In Fig. 8 a plurality of units 5 and 6 are shown in diagrammatic form and disposed to form an inclosure of irregular outline, it being intended to modify an inclosure of this character as may be found necessary, 30 and in some instances to construct an inlet or harbor recess 44 and whereby boats may run into said recess or harbor inlet and be shielded from storms or heavy wave effects. When an inclosure is produced as shown by 35 40 Fig. 8 it may serve as the base or foundation support for a superstructure and the wall thus produced around the inclosure will be further strengthened by the body of water inclosed thereby after the manner of a lagoon.

After the units 5 have been sunk in their proper positions by being partially filled with concrete it is proposed to fill the same with cement or concrete completely and 45 thereby give them stability and placement and also strengthen them to resist strain and effectively perform the function for which they have been erected.

From the foregoing it will be seen that 50 the units 5 and the braces in their various forms generalized under the units 6 with the several modifications hereinbefore explained will be applicable for various purposes and to adapt the same to different uses 55 changes in the general dimensions and proportions may be made at will.

What is claimed as new is:

1. A deep sea construction comprising 60 tubular units having closed bottoms for receiving a filling of material of sufficient weight to sink said units until the closed bottoms thereof rest upon the sea bottom, means extending between said units having longitudinal slidale connections therewith,

whereby said tubular units may have an 65 automatic settling movement with relation to said means, and tubular sections of different widths applied to the upper ends of the tubular units to give the latter a uniform top level. 70

2. In a deep sea construction comprising tubular units having inner annular ledges secured thereto for strengthening the same, means extending between said means and 75 units permitting relative vertical movements thereof, and material contained in said tubular units of sufficient weight to sink said units to a firm foundation on the sea bottom so that in case of an irregular bottom 80 said tubular units may have an automatic settling movement in relation to said means.

3. A deep sea construction comprising tubular units consisting of a plurality of superposed sections, the lowermost sections 85 being closed at one end, a filling medium for said units adapted to cause successive sections of the tubular units to sink until sufficient sections have been secured together to enable the closed end to rest upon the sea 90 bottom and the upper ends of said tubular units to project above the water level, flanged elements secured to each section and placed in vertical alinement, and means disposed between the tubular units and slidably engaged by said elements to permit the tubular units to have an automatic settling movement.

4. In a deep sea construction, tubular units having lower closed ends for receiving 100 a filling of plastic material adapted to gradually sink said units, annular ledges secured to the lower portions of the tubular units, connecting means between the tubular units permitting relative vertical movements thereof whereby the tubular units may have an automatic settling movement 105 in relation to the connecting means, said filling of plastic material and said tubular units becoming a part of the completed 110 structure.

5. A structure of the class described comprising tubular units having lower closed ends, means extending between said units, devices connecting said means and tubular 115 units and so arranged as to permit relative vertical movements thereof, tubular sections secured to the upper ends of the tubular units to give the latter a uniform top level in accordance with their settling 120 movements, and a filling of plastic material introduced into the tubular units for sinking the same, said tubular units resting permanently in position and forming a part of the finished structure. 125

6. A structure of the class described comprising tubular units, connecting units for the tubular units consisting of a plurality

- of braces with which the tubular units are slidably associated for permitting automatic settling movements, means connecting a plurality of said braces so as to permit relative vertical movements thereof, and a filling of plastic material in the tubular units for sinking said units to a solid foundation at the sea bottom and forming part of the finished structure.
- 10 7. A structure of the class described comprising tubular units, attaching means secured to said units and projecting therefrom, connecting units disposed between the tubular units and slidably engaging said attaching means whereby the tubular and connecting units may have relative vertical movements to provide for an automatic settling movement, and a plastic filling in the tubular units forming part of the finished structure and of sufficient weight to sink said units until the lower ends thereof reach the sea bottom.
8. A construction of the class described comprising, tubular units, connecting units for the tubular units consisting of brace devices extending in various directions from the several tubular units to other similar units, and means connecting said brace devices and tubular units for permitting relative movements thereof, and a filling medium in said tubular units of sufficient

weight to embed the lower ends of the latter in the sea bottom.

9. A construction of the class described comprising, tubular units, connecting units for the tubular units, consisting of brace devices running from one tubular unit to another and intersecting, means located at the intersection of said brace devices for connecting the latter and permitting relative vertical movements thereof, and a plastic filling in said tubular units of sufficient weight for sinking the latter in place.

10. A construction of the class described comprising tubular units disposed in outer alined and inner supporting groups, connecting units for the tubular units consisting of brace devices extending between the several groups and from one unit to another and intersecting at various angles, and means located at the intersection for connecting the brace devices for connecting the latter and permitting relative vertical movements thereof, and a plastic filling material in the tubular units.

In testimony whereof I have hereunto set my hand in presence of a subscribing witness.

WILHELM GRIESSEER.

Witness:

CHAS. S. HYER.
